LIFTING JACK

Filed Dec. 15, 1928

UNITED STATES PATENT OFFICE

GUNNAR JENSEN, OF RACINE, WISCONSIN, ASSIGNOR TO WALKER MANUFACTURING COMPANY, OF RACINE, WISCONSIN, A CORPORATION OF WISCONSIN

LIFTING JACK

Application filed December 15, 1928. Serial No. 326,316.

This invention relates to new and useful improvements in lifting jacks, and more particularly to an improved jack of the type embodying a plurality of lifting screws which are successively elevated to obtain a long lift in proportion to the height of the jack when lowered.

The principal object of the invention is to provide improved means for yieldably resisting rotary movement of one of the screw members while permitting same to travel freely in a vertical direction. This means consists of a wire spring which is anchored in the lower end of the screw member and is formed with outwardly bowed spring loops which engage the inner cylindrical walls of the bore in the stationary standard through which the screw member travels.

Other objects and advantages of this invention will be more apparent from the following detailed description of one approved form of mechanism embodying the principles of this invention.

In the accompanying drawings:

Fig. 1 is a longitudinal vertical section through the lifting jack, in partially elevated position.

Fig. 2 is a transverse horizontal section, on an enlarged scale, taken substantially on the line 2—2 of Fig. 1 and looking in the direction of the arrows.

The stationary supporting standard, in the form here shown, consists of an integral casting formed with an upstanding cylindrical portion 1 and a comparatively large flat supporting base 2, there being strengthening webs 3 between the base and the vertically extending tubular portion of the standard. A cylindrical bore 4, having comparatively smooth cylindrical side walls, extends vertically through the standard, this bore being closed at the bottom in any suitable manner as by the closure plate 5. The upper end of the standard is enlarged, as at 6, to form a support for the driving gear or nut 7, as hereinafter described. An inwardly projecting flange 8 at the top of the standard, and an upper spaced bracket loop 9 extending from the head 6, are formed with vertically aligned openings adapted to serve as guides

for the threaded sleeve 10, which serves as the outer lifting screw.

The hub 11 of the driving gear 7 is internally threaded so as to serve as a nut, through which the external threads 12 of the sleeve 10 are threaded. An anti-friction bearing comprising the upper and lower raceways 13 and 14 and an annular series of balls 15 confined in a cage 16, serves to support the driving gear 7 and nut 11 from the head 6 of the standard. The nut 11 is of slightly less vertical height than the distance between head 6 and the upper portion of bracket 9.

A beveled driving pinion 17 is rotatably supported on a stud 18 secured in an enlargement or boss 19 at one side of the upper end of standard 1. The outwardly extending hub 20 of pinion 17 is formed with a non-circular socket 21 to receive the correspondingly shaped end 22 of the detachable jack handle.

Stud 18 is formed with a main cylindrical portion on which the pinion 17 is journaled, and has an enlarged head or annular shoulder 23 seated in a correspondingly shaped recess 75 in the bottom of socket 21, whereby the pinion is held on the stud but permitted to rotate. The stud 18 has a shoulder 24 engaging the outer face of the enlargement 19 on standard 1, and a restricted end portion 25 secured in a socket 26 in the boss 19 by means of a pin or rivet 27.

The upper end portion of sleeve 10 is internally threaded, as indicated at 28, and an inner lifting screw 29 meshes within the threads 28. A lifting head 30 for engaging and supporting the load is secured at the upper end of screw 29. A stop 31 which may be formed by striking upwardly a portion of one of the threads, or may alternatively be 90 in the form of an interposed pin, is provided near the lower end of screw 29 to engage the lower end of the nut formed by threads 28 so as to limit the upward movement of screw 29 out of sleeve 10. A similar stop 32 is 95 formed near the lower end of the externally threaded portion 12 of sleeve 10, this stop 32 engaging a sheared-off thread in the lower end of nut 11 and serving as a means for rotating the sleeve 10. An external stop 33 near 100

the upper end of sleeve 10 limits the lowering movement of this threaded sleeve and also serves as a means for rotating sleeve 10 by engaging a sheared-off thread at the top of nut 11.

5 When a load is supported by the head 30, the inner screw 29 will be held against rotation. If the sleeve 10 is rotated, the non-rotating screw 29 will be forced to move vertically through the nut 28 in the upper end of sleeve 10. When the handle 22 is rotated, the rotary movement will be imparted to the driving nut 11 through the intermeshing gears 7 and 17. If the threaded sleeve 10 rotates 10 with the nut 11, it will serve to cause the nut 28 to rotate and thus screw up or down the non-rotary inner screw 29. If, on the other hand, the sleeve 10 is held against rotation, it will be moved up or down through the rotating nut 11, thus carrying the inner load-supporting screw 29 bodily with it. As a net result of these movements, a continuous rotary movement imparted to the handle 22, will cause the two screws 29 and 10 to be moved to 15 their extreme vertical limits in one direction or the other. This can only take place, however, with the structure thus far described, when a load is supported on head 30 so as to hold the inner screw against rotation. In 20 the absence of such a load, the screws will merely turn bodily with the nut 11 and not change their vertical positions, whatever these may be.

According to the present invention, means 35 is provided to yieldably resist the rotary movement of sleeve 10, so that this sleeve will move vertically through driving nut 11, even though no load is supported by the inner screw 29. In the example here shown, a pair of diametrically opposed radial holes or 40 openings 34 are formed in the lower end portion of threaded sleeve 10. Positioned at 90 degrees to the openings 28 are a pair of radial slots 35 open at their lower ends.

45 A wire spring 36 consists of a central straight portion 37 from each end of which is bent a spring loop 38 terminating in an inwardly extending end portion 39, the two ends 39 projecting toward one another. The straight central portion 37 of the spring is inserted in the slots 35 and the bottom edges of these slots are peened over the wire to hold it in place. The spring ends 39 are snapped into the holes 34. The outwardly bowed spring loops 38 will frictionally engage the inner cylindrical surface 4 of the bore of the standard, and will offer a greater resistance to 50 rotary movement of the sleeve in the bore than it does to vertical movement of the sleeve through the bore. As a result, when driving nut 11 is rotated, the sleeve 10 will not rotate, but will be moved vertically through the nut until one of the upper or 55 lower limit stops 33 or 32 engage the sheared

threads on the upper or lower faces of nut 11, after which the sleeve will be forced to rotate with driving nut 11 in spite of the frictional resistance offered by the bowed spring loops 38.

70 In operation, the jack may be placed beneath the load with both screws 10 and 29 completely lowered and nested within the standard. At this time the inner screw 29 will not be in engagement with the load and there will be nothing to prevent the rotation of this inner screw. However, when the driving nut 11 is rotated in the proper direction, the screw sleeve 10 will be elevated through 75 the driving nut 11, since this sleeve is held against rotation by the frictional resistance of spring loops 38 against the inner surface of the bore in the standard. This movement will continue until the stop 32 has engaged the sheared thread on the under surface of nut 11, after which the sleeve 10 will be forced to rotate with the driving nut. However, before this position is reached, the head 30 on inner screw 29 will have engaged the load, so that when sleeve 10 rotates with the nut 11, 80 the rotary nut 28 in the upper end of sleeve 10 will serve to elevate the inner screw 29.

85 The screws are lowered by turning the handle 22 in the reverse direction, and thus reversing the direction of rotation of driving nut 11 and sleeve 10. The sleeve 10 will be held from rotation by the bowed springs 38 so that it will be lowered completely into the 90 standard, that is until stop 33 engages the sheared off thread on the upper surface of nut 11, after which it will rotate with the nut 11 to lower the inner screw 29 into the standard, so long as screw 27 is held against rotation by its engagement with the load, or in 95 any other manner.

100 I claim:

1. In a lifting jack comprising a standard having a cylindrical bore, a lifting member movable longitudinally through the bore, and means supported by the standard and having rotatable engagement with the lifting member for moving it longitudinally in the bore, means for yieldingly resisting rotary movement of the member in the bore comprising a wire spring, the inner end portion of the member being formed with a plurality of circumferentially spaced substantially radial openings, the intermediate portion of the spring being engaged in certain of the openings, and each end portion being looped outwardly and circumferentially of the member with the free end inserted inwardly through another opening.

110 2. In a lifting jack comprising a standard having a cylindrical bore, a lifting member movable longitudinally through the bore, and means supported by the standard and having rotatable engagement with the lifting member for moving it longitudinally in the bore, means for yieldingly resisting ro- 115

5 tary movement of the member in the bore comprising a wire spring, the inner end portion of the member being formed with a plurality of circumferentially spaced substantially radial openings, the spring being positioned in the openings so as to form an outwardly bowed circumferentially extending loop adapted to engage the inner surface of the bore.

10 3. In a lifting jack comprising a standard having a cylindrical bore, a lifting member movable longitudinally through the bore, and means supported by the standard and having rotatable engagement with the lifting member for moving it longitudinally in the bore, means for yieldably resisting rotary movement of the member in the bore comprising a wire spring, the inner end portion of the member being formed with a plurality of circumferentially spaced substantially radial openings, the spring being positioned in the openings so as to form outwardly bowed circumferentially extending 15 spring loops adapted to engage the inner surface of the bore.

20 4. A lifting jack comprising a standard having a cylindrical bore, a driving nut rotatably supported on the standard, an interiorly and exteriorly threaded sleeve threaded within the nut and adapted for longitudinal movement in the bore, a second lifting screw threaded within the sleeve, means for rotating the nut, and means for yieldably resisting rotary movement of the sleeve 25 within the bore comprising a wire spring, the lower end portion of the sleeve being formed with a plurality of circumferentially spaced substantially radial openings, the spring being engaged in a pair of opposite openings, and each end portion being looped outwardly and circumferentially of the sleeve with the free end inserted inwardly through another of the openings.

30 5. A lifting jack comprising a standard having a cylindrical bore, a driving nut rotatably supported on the standard, an interiorly and exteriorly threaded sleeve threaded within the nut and adapted for longitudinal movement in the bore, a second lifting screw threaded within the sleeve, means for rotating the nut, and means for yieldably resisting rotary movement of the sleeve within the bore comprising a wire spring, the lower end portion of the sleeve being formed with a plurality of circumferentially spaced radial openings, the spring being positioned in the openings so as to form outwardly bowed circumferentially extending spring loops adapted to engage the inner surface 35 of the bore.

6. A lifting jack comprising a standard having a cylindrical bore, a driving nut rotatably supported on the standard, an interiorly and exteriorly threaded sleeve threaded within the nut and adapted for

longitudinal movement in the bore, a second lifting screw threaded within the sleeve, means for rotating the nut, and means for yieldably resisting rotary movement of the sleeve within the bore comprising a wire 40 spring, the lower end portion of the sleeve being formed with a plurality of circumferentially spaced substantially radial openings, the spring being positioned in the openings so as to form an outwardly bowed circumferentially extending spring loop adapted to engage the inner surface of the bore.

7. A lifting jack comprising a standard having a cylindrical bore, a driving nut rotatably supported on the standard, an interiorly and exteriorly threaded sleeve threaded within the nut and adapted for longitudinal movement in the bore, a second lifting screw threaded within the sleeve, means for rotating the nut, and means for yieldably resisting rotary movement of the sleeve within the bore comprising a wire 45 spring consisting of a substantially straight central portion and a pair of spring loops bent in opposite directions in the same plane from the ends of the central portions, the free ends of the loops projecting inwardly toward one another, the lower end of the sleeve being formed with a pair of substantially diametrically opposed open slots and a pair of substantially opposed radial openings, the straight central portion of the spring being positioned in the slots and held in place by partially closing the open ends of the slots, and the free ends of the spring being mova- 50 bly engaged in the openings.

8. A lifting jack comprising a standard having a cylindrical bore, a driving nut rotatably supported on the standard, an interiorly and exteriorly threaded sleeve 55 threaded within the nut and adapted for longitudinal movement in the bore, a second lifting screw threaded within the sleeve, means for rotating the nut, and means for yieldably resisting rotary movement of the sleeve within the bore comprising a wire spring consisting of a substantially straight central portion and a pair of spring loops bent in opposite directions in the same plane from the ends of the central portions, the free 60 ends of the loops projecting inwardly toward one another, the lower end of the sleeve being formed with a plurality of substantially radial openings in which the spring is positioned, the straight central portion of the spring being locked in certain of the openings and the free end portions being 65 slidably positioned in other openings.

9. A lifting jack comprising a standard having a cylindrical bore, a driving nut rotatably supported on the standard, an interiorly and exteriorly threaded sleeve threaded within the nut and adapted for longitudinal movement in the bore, a second lifting screw threaded within the sleeve, 70

means for rotating the nut, and means for yieldably resisting rotary movement of the sleeve within the bore comprising a wire spring consisting of a substantially straight central portion and spring loops extending from the respective ends thereof, the lower end of the sleeve being formed with a pair of diametrically opposed radial open slots in which the spring is positioned and locked in place by peening inwardly the edge portions of the slots.
